UNITED STATES PATENT OFFICE.

FRANK RUDOLPHI, OF NEW YORK, N. Y., ASSIGNOR TO AMERICAN CAN COMPANY, A CORPORATION OF NEW JERSEY.

CAN-CLOSING MACHINE.

1,327,966.

Specification of Letters Patent. Patented Jan. 13, 1920.

Application filed December 1, 1915. Serial No. 64,473.

To all whom it may concern:

Be it known that I, FRANK RUDOLPHI, a citizen of the United States, residing in New York, in the county of New York and State 5 of New York, have invented a new and useful Improvement in Can-Closing Machines, of which the following is a specification.

The invention relates to can closing machines, and more particularly to such machines wherein rotary seam forming and closing rolls are employed. These rolls require very accurate adjustment, the first operation roll for the purpose of preliminarily curling the flanges of the can elements (body 10 and end) and interlocking the same to make a partly formed seam, and the second operation roll to flatten and complete said seam to entirely close it and make it hermetic. After said rolls have been accurately 15 adjusted it is often necessary to omit said second operation so that the filled cans, having ends attached, will come from the closing machine with partly open seams which are not air, gas or steam tight, whereby the 20 cans may be processed or further processed (with escape of air, gas or steam) before their seams are hermetically closed. It is detrimental for this purpose to remove the 25 second operation roll as the rotary seaming head would thereby be unbalanced; it is also very undesirable to leave the second operation roll on the seaming head, but adjusted radially out of operation by its 30 adjusting means because its previous careful adjustment is thereby lost. The present improvement has for its objects to overcome 35 said objections by providing means whereby the roll which is not desired to operate may be left on the seaming head, but may be 40 thrown out of operation by devices independent of its adjusting means; so that, when it is desired to again use said roll, it may be merely thrown back to operative 45 position and thereby caused to resume its former perfectly adjusted position.

With such objects in view, as well as the attainment of all other features of usefulness and advantage which are inherent in the improved can closing machine, the invention 50 consists in the parts and combinations thereof hereinafter set forth and claimed.

In order to make the invention more clearly understood there are shown in the accompanying drawings means for carrying 55 the same into practical effect, without limit-

ing the improvements, in their useful applications, to the particular construction which, for the purpose of example, has been made the subject of illustration.

In the said drawings:—

Figure 1 is a vertical section of a seaming head for can closing machines, the same embodying the invention.

Fig. 2 is a side view of the same.

Fig. 3 is a bottom plan view of the seaming head.

Fig. 4 is a horizontal section on line IV—IV of Fig. 1.

Fig. 5 is an elevation, partly in section on line V—V of Fig. 6, on a larger scale, of a 70 portion of the seaming head.

Fig. 6 is an elevation looking toward the left hand side of Fig. 5.

Fig. 7 is a horizontal section on line 75 VII—VII of Fig. 5.

Referring to the drawings, 87 indicates a rotary two-operation seaming head. The seaming head consists of body 140 in the form of a disk having a diametrical guideway 141 therein. Formed integral with the 80 disk, and projecting below its face, are two parallel flanges 142, which form the walls of the guideway 141. The disk also has upwardly extending flanges 142', and integral therewith a centrally located vertical hollow 85 spindle 143, upon which is slidably mounted a sleeve 144 to which are secured two diametrically opposite first and second operation roller actuating cams 145 and 145', which will be hereinafter described. Ex- 90 tendsing vertically within the spindle 143 is a hollow chuck spindle 147 carrying at its lower end and below the seaming head body 140 an upper chuck member 148 which co- 95 operates with the usual or any suitable can lifter to hold the can fixed during the seaming operation. Located within the chuck spindle 147 is a vertical reciprocating knock- 100 out rod consisting of an upper section 149 and a lower section 150 connected by a scarf joint 151. The lower section 150 is provided at its lower extremity with a can engaging pad 152 which nests within a recess 153 in the chuck member 148 while a can is being seamed but which descends and assists in 105 extracting the can from the seaming head when the seam is completed.

The lower parts of the two flanges 142 are horizontally channeled as at 154 to form the 110 slideway or track 141 for two diametrically

opposed first and second seaming roll slides 156 and 156'. The upper and lower surfaces of the channels 154 are protected from wear by interchangeable copper linings 157 which 5 may be replaced when worn or corroded, thus eliminating wear upon the disk itself.

Projecting downwardly from the under side of the slides 156 and 156' are L-shaped brackets 158 and 158' which support the first 10 and second operation rolls 159 and 159'. The first operation roll is provided with a comparatively deep flange-turning peripheral groove 160 and the second operation roll with a comparatively shallow flange- 15 flattening and closing groove 160'. These rolls are axially mounted and journaled upon roller pins 161 between which and the seaming rollers are located roller bearing cages 162 which retain vertical anti-friction 20 rollers 163. The roller pins 161 are held in place by tangential locking pins 164 which extend horizontally through the seaming roll slides 156 and 156' and engage recesses 165 in the roller pins, thus retaining the 25 same in place. The brackets 158 and 158' are protected from wear occasioned by the seaming rolls by plates 166 interposed between the seaming rolls and the said brackets. Interposed between the seaming rolls 30 and the slides 156 and 156' are hardened steel washer plates 167. These plates take practically all of the wear caused by the rolls and protect the slides and brackets which, for the object of reducing weight, 35 are constructed of suitable metal and may be replaced when desired.

It is necessary that these rolls be susceptible to a very accurate and fine adjustment in order that perfect hermetic seams may be 40 produced. To facilitate this there are provided in the upper faces of the seaming roll slides, channels 168 with under cut walls adapted to receive adjusting slides 170 and 170' which are slidable radially within the 45 said channels. These slides have in their upper surfaces, lateral notches or recesses 171 adapted to receive the lower ends of levers 172 and 172', which are actuated by the cams 145, 145' as will be described later. 50 Threaded into the ends of the adjusting slides are horizontal adjusting screws 173 the heads 174 of which project below the lower surfaces of the adjusting slides and engage in notches 175 in the upper faces of 55 the seaming roll slides 156 and 156', thus preventing longitudinal displacement of the adjusting slides in relation to the said seaming roll slides unless said screws be turned. Threaded into and projecting vertically 60 from the seaming roll slides are cap screws 176 which extend through slots 177 in the adjusting slides 170 and 170' and which lock together the adjusting slides and the seaming roll slides in their desired and adjusted 65 positions relative to each other. In adjust-

ing the seaming rolls the adjusting slides may be considered as stationary, being held so by the cam-actuated levers 172 and 172' engaging the lateral notches 171. The cap screws 176 being loosened, the horizontal adjusting screws 173 are turned, their heads 174 engaging the notches 175 in the seaming roll slides, and forcing the slides with the seaming rolls either inwardly or outwardly as the case may be until the desired seam is 70 obtained. The set screws 176 are then tightened, locking the slides together in their adjusted positions.

Between the upper flanges 142' of the seaming disk, and substantially above the seaming roll slides, are pivotally mounted, by means of pivot pins 178 and 178', the said first and second operation cam-actuated levers 172 and 172' the lower ends of which engage the lateral recesses 171 in the adjusting slides 170 and 170'. The pivot pins 178 and 178' are prevented from rotating within their bearings by lugs 179 which engage flat surfaces 180 on the sides of the heads 181 of said pivot pins. These pins are 80 removably held in place by leaf springs 182 which are pivotally secured to the flanges 142', the other extremities engaging notches 184 in the heads 181. The pivot pins 178 and 178' are further provided with grease 85 cups 185 which furnish lubrication for the said levers. The upper ends of these levers carry cam rollers 186 and 186' which bear against the cams 145 and 145' carried by the sleeve 144 on the seaming head spindle 143. 90 The upper ends of the levers are also provided with outwardly projecting solid metal weighted heads 187 and 187' which serve to some extent in counterbalancing the weight 95 of the seaming rolls and slides when released by the cams 145 and 145' and thrown outwardly out of operative position by the centrifugal force of the revolving head, thus avoiding the danger of breakage that might otherwise result from a too sudden or violent 100 outward movement of the seaming rolls and their slides.

The sanitary or double seaming is accomplished by two operations. The first operation is to form a curl on the end flange or on 115 both the cam end and cam body flanges, leaving said flanges interlocking by a loose partly finished seam, and this is performed by the comparatively deep groove 160 in the first operation roll 159. The second operation is to complete the seam commenced by the first roll and flatten out the same and render it absolutely impervious to air, which is done by the comparatively shallow or flat 120 annular groove 160' in the second operation roll 159'.

It is quite frequently desirable to throw the second operation roll out of operative position without disturbing its adjustment by the slide 170' in relation to the seaming 130

head, or the equilibrium of the seaming head by bodily removing it from the head. For example, in adjusting the first operation roll to make a correct first seam, it is imperative that the first seam formed should not be touched by the second operation roll so as to flatten or otherwise change its shape, until, by experiment, the partial seam has been made satisfactory. Again it is often necessary in canning certain food stuffs that the first loose seam should be formed, and before the seam is rendered air tight by the action of the second operation roll, to remove the can from the closing machine to an exhaust box where the can and contents are heated for the necessary length of time under a suitable temperature (of approximately 200° F.) in order that certain gases liable to cause swell or spring heads of the cans be exhausted through the comparatively loose first seam, and to then return the can to the closing machine for the second and finishing seaming operation. The means for thus throwing the second operation roll out of engagement with the can without removing the same from the seaming head is as follows: Mounted within the second operation lever 172' and about its pivot pin 178' is an eccentric bushing 188 having a substantially rectangular head 189 which nests within a corresponding recess 190 in the side of the lever 172'. The bushing 188 is thus held against rotation in its desired position, and with its head 189 flush with the side of the lever, and against lateral displacement between the walls 142' which form the bearings for the lever pivots. In operative position the thick part 191 of the bushing 188 is toward the center of the head and the thin part 192 turned outwardly. To disengage the second operation roll 159' as mentioned, the pivot pin 178' is removed and the lever 172 lifted out. The bushing 188 is then given one half turn bringing the thin part 192 of the same toward the center of the seaming head and the thick part 191 opposite. The lever is then replaced and the pivot pin inserted. In replacing the lever and its pivot and at the same time engaging the lower end of the lever with the notch 171, the slide 156' has to be moved a little outward from its former position. The second operation roll is now out of operation and the head is adapted to make a first seam only. In order that no mistake may be made as to how the bushing 188 should be turned, either to seam or not to seam, the head of the same on the sides adjacent the thick part 191 and thin part 192 is stamped "Seam" and "No seam" respectively, and the side of the lever is stamped with an arrow shown in the drawings (Fig. 5). By thus giving the bushing one half revolution thereby moving the thick part of the same outward, in relation to the

seaming head, and the pivot pin 178' being considered as stationary, the pivotal center of the lever has been moved outwardly or farther away from the center of the seaming head. This being the case, when the cam 145', on the vertically sliding sleeve 144, actuates the upper end of the lever 172', causing the same to oscillate about its pivot 178', the innermost limit of the arc described by the lower end of the said lever is farther away from the center of the head, and the roll 159' will not move as far inwardly as it did before the eccentric bushing 188 was given its half turn, and cannot operate on the can or can end flanges. 80

At the upper part of the cam carrying rotary sleeve 144 and integral therewith is an annular collar 198 provided with a peripheral groove 199 which carries a split non-rotary ring 200. This ring is provided with horizontal diametrically opposed channels 201 adapted to receive two sliding shoes 202. These shoes are provided with trunnions 203 which are pivoted to the arms of a yoke 204 on one end of a seaming roll actuating lever 205. The lever 205 is or may be pivotally mounted at its center upon the casing of the machine by means of an eccentric pivot pin, by which a very fine vertical adjustment of the sleeve 144 may be had. The inner extremity of the lever 205 is provided with a roller 207 which engages a grooved cam 208 fixed on the vertical cam shaft of the machine. It will be seen that as the cam rotates, the lever 205 will oscillate vertically causing the rotary cam carrying sleeve 144 to reciprocate upon the spindle 143 of the seaming head body while the same is revolving, and causes the first and second operation cams 145 and 145' to successively actuate the seaming roll levers, slides and rolls. The high part of the first operation cam 145 is located higher up on the sleeve than the high part of the second operation cam 145'. This is because the seaming operation takes place while the cam sleeve 144 is traveling upwardly, and the high part of the first operation cam 145 must actuate the first operation lever, slide and roll before the high part of the second operation cam 145' actuates the lever slide and roll for the second operation. After the seaming operation is completed and the lever 205 has depressed the cams the centrifugal force generated by the fast rotation of the seaming head will cause the rolls 120 to disengage themselves from the can and slide outwardly together with their slides and levers back to normal position and ready for another operation. 110

What is claimed is—

1. In a can closing machine, a seaming head having, in combination: a plurality of seaming rolls; means for independently adjusting said rolls to any position within limits; and means independent of said adjust- 130

ing means for moving one of said rolls together with its adjusting means into inoperative position while on the seaming head, leaving the other roll adjusted for a seaming operation, and for restoring the inoperative roll to its adjusted position by the reversal of such throwing-out movement.

2. In a can closing machine, a seaming head having, in combination: first and second operation seaming rolls; means for independently adjusting said rolls radially to any position within limits; and means independent of said adjusting means for moving the second operation roll together with its adjusting means into inoperative position while in the seaming head; and for restoring the inoperative roll to its adjusted position by the reversal of such throwing-out movement.

3. In a can closing machine for uniting can ends to can bodies by means of interfolded and interlocked seams, in combination: a seaming head carrying a plurality of seaming rolls, two independent adjusting means for one of said rolls, one of said adjusting means being a normal operative adjustment to regulate the pressure of the roll during the seaming operation while forming the interlocking seam, and the other of said adjusting means moving the roll together with its pressure regulating adjusting means into inoperative position, and being a disrupting means for temporarily disrupting the operative adjustment and the action of the roll during a cycle of the seaming operation of the remaining roll and allowing the replacing of the inoperative roll into its said normal operative adjustment.

4. In a can closing machine for uniting can ends to can bodies by means of interfolded and interlocked seams, in combination: a seaming head carrying a plurality of seaming rolls, means for adjusting the normal operative relation of said rolls whereby they will operate with more or less pressure while forming interlocked seams uniting can ends to can bodies, and additional independent adjusting means for moving one of the rolls together with its pressure regulating adjusting means into inoperative position and temporarily disrupting the adjustment of said roll during a seaming operation of the remaining roll without changing the normal operative adjusting means of said inoperative roll.

5. In a can closing machine, a seaming head having, in combination: first and second operation seaming rolls; means for independently adjusting said rolls radially; and an eccentric independent of said adjusting means for throwing out of operation the second operation roll without removing it from the head, and for restoring it to its adjusted position by the reversal of such throwing-out movement.

6. In a can closing machine, a seaming head having, in combination: a plurality of slides mounted to operate radially on said head; levers for operating said slides; pivots connecting said levers with the seaming head; means for adjusting the connections between said levers and slides; vertically slidable cams for actuating said levers; an eccentric connected with one of said levers, said eccentric being adjustable to make the 70 adjusted throw of its lever operative or inoperative; and seaming rolls mounted on said slides.

7. In a can closing machine, a seaming head having, in combination: a plurality of 80 slides mounted to operate radially on said head; a second series of slides mounted to be radially adjusted on the first mentioned slides; means for adjusting the slides of said second series; levers for operating both 85 series of slides in unison, said levers engaging the slides of said second series; pivots connecting said levers with the seaming head; vertically slidable cams for actuating said levers; an eccentric connected with one of 90 said levers, said eccentric being adjustable to make the throw of its lever operative or inoperative; means for holding said eccentric in either of its two defined positions, and seaming rolls mounted on said first men- 95 tioned slides.

8. In a can closing machine, a seaming head having, in combination: a plurality of slides mounted to operate radially on said head; a second series of slides mounted to be 100 radially adjusted on the first mentioned slides; means for adjusting the slides of said second series; levers for operating both series of slides in unison, said levers engaging the slides of said second series; pivots 105 connecting said levers with the seaming head; vertically slidable cams for actuating said levers; an eccentric mounting for one of said levers, said mounting being adjustable to make the throw of its lever operative or in- 110 operative; and seaming rolls mounted on said first mentioned slides.

9. In a can closing machine, a seaming head having, in combination: a plurality of 115 slides mounted to operate radially on said head; a second series of slides mounted to be radially adjusted on the first mentioned slides; means for adjusting the slides of said second series; levers for operating both series of slides in unison, said levers engag- 120 ing the slides of said second series; pivots connecting said levers with the seaming head; vertically slidable cams for actuating said levers; an eccentric surrounding the pivot pin of one of said levers, said eccentric 125 being adjustable to make the throw of its lever operative or inoperative; and seaming rolls mounted on said first mentioned slides.

10. In a seaming head, the combination of a slide, a lever for actuating said slide, a 130

cam for actuating said lever, a seaming roll adjustably connected with said slide, and means for adjusting the pivot of said lever.

11. In a seaming head, in combination: a head body; seaming roll slides slidable inwardly and outwardly therein; first and second operation seaming rolls carried by said slides; a chuck member coöperating with the said rolls; cam actuated levers 10 pivotally mounted in the said head body for operating the said slides and rolls; and an eccentric bushing forming the pivotal bearing of the said second operation seaming roll lever, said bushing adapted to be so manipulated as to throw the said second operation roll in to and out of operative position.

12. In a seaming head, in combination: a seaming head body; seaming roll slides movable inwardly and outwardly thereon; adjusting slides adjustably secured to the seaming roll slides; seaming roll actuating levers pivoted in the said body; and an eccentric bushing supporting one of the said levers, said bushing adapted to be so manipulated as to throw one of the seaming rolls out of operative position independently of the seaming roll adjusting means.

13. In a seaming head, in combination: a seaming head body; a centrally located vertical spindle; first and second operation seaming roll slides movable inwardly and outwardly relative to the axis of the seaming head; first and second operation seaming rolls carried by the said slides; first and second operation seaming roll adjusting slides 35 adjustably secured to the said seaming roll slides; first and second operation seaming

roll actuating levers pivotally mounted in the said body; an eccentric bushing supporting the said second operation lever, said bushing being adapted to be manipulated to throw the said second operation roll into and out of operative position without disturbing the adjustment of its roll; means for retaining the said bushing in its adjusted positions and a sleeve, slidable vertically on the said spindle and carrying first and second operation lever actuating cams.

14. In a seaming head,* in combination: a seaming head body; a centrally located vertical spindle; first and second operation seaming rolls slides slidable radially therein; first and second operation rolls carried by the said slides; first and second operation seaming roll adjusting slides adjustably secured 50 to the said seaming roll slides; first and second operation seaming roll actuating levers pivotally mounted in the said body; an eccentric bushing having a shouldered head and supporting the said second operation lever, said bushing being adapted to be turned, thus moving the pivot point of the said lever toward or away from the center of the seaming head so as to throw the said second operation roll, into or out of operative 55 position without disturbing the adjustment of the said second operation roll; and a recess in the side of the said lever adapted to receive the shouldered head of the said eccentric bushing to hold the latter in 60 either of two positions.

In testimony whereof I have affixed my signature hereto.

FRANK RUDOLPHI.
